UNITED STATES PATENT OFFICE.

MAX WERTHEIM, OF PIETERMARITZBURG, NATAL, SOUTH AFRICA.

SUGAR-CANE CUTTER.

1,392,377.

Specification of Letters Patent. Patented Oct. 4, 1921.

Application filed October 1, 1919. Serial No. 327,815.

To all whom it may concern:

Be it known that I, MAX WERTHEIM, a subject of the King of Great Britain and Ireland, residing at Pietermaritzburg, in the 5 Province of Natal, South Africa, have invented certain new and useful Improvements in Sugar-Cane Cutters, of which the following is a specification.

This invention relates to an apparatus for 10 cutting cane, the object of the invention being to provide an apparatus of this character whereby the cane is felled and topped ready for the grinding mill, so that it will no longer be necessary to perform these 15 operations by hand.

A further object of the invention is to provide a machine of the character set forth, which machine is provided with a horizontally operating cutting knife which can be 20 moved to different positions for felling the cane, and with a vertically acting knife for removing the tops from the felled cane, said knives being power operated.

A further object of the invention is to 25 provide a machine of the character set forth having means for receiving the felled cane, and leveling the tops thereof so that the canes are evenly presented to the top-cutting knife.

30 With the foregoing and other objects in view, all of which will appear as the description proceeds, the invention consists in the novel features of construction and combination of parts which will be more 35 fully set forth hereinafter and particularly pointed out in the claims.

In the drawings accompanying and forming part of this specification,

Figure 1 is a side elevation, partly broken 40 away, of a machine constructed in accordance with the present invention;

Fig. 2 is a transverse sectional view taken approximately on the line 2-2 of Fig. 1;

Fig. 3 is a plan view of the machine;

45 Figs. 4 and 5 are transverse sectional views, on a smaller scale, illustrating different positions of the cane transferring member or carrier; and

Fig. 6 is a detail side view of the topping 50 knife.

The same characters of reference designate the same parts in the different figures of the drawings.

The apparatus herein illustrated com-

prises a frame or truck formed of a pair 55 of U beams 2 secured by means of eye bolts 3 to an axle 4, on the opposite ends of which are mounted a pair of road wheels 5. On the upper side of the beams or girders 2 are mounted and secured by means of bolts, two 60 pair of wooden beams or timbers 6, the members of each pair being spaced from each other approximately at the center of the machine to permit a trough 8 to be supported between the ends of such timbers, 65 the bottom of the trough being secured to the axle by means of eye-bolts 7. This trough 8 extends vertically above the beams to a suitable height and has attached thereto a superstructure 9, preferably formed of 70 interwoven wire secured to a frame made of piping. As clearly shown in Fig. 1, the sides of this superstructure are inclined with relation to the side walls of the trough 8, so that it is wider at the top than the distance between the side walls of said trough. 75

For permitting the apparatus to be adjusted vertically, I have illustrated herein two pairs of wheels 10 and 11, respectively, one pair at each end of the apparatus. Each 80 of these wheels 10 and 11 is mounted for rotation on a stud axle secured to an upright member or rod 12 which is slidable in a bracket secured to opposite ends of the frame. The rods 12 carrying the wheels 10 85 are shown in Fig. 1 passing through two small brackets 13, while the rods carrying the wheels 11 are illustrated passing through a wider bracket 14. All of the rods 12 are secured in any adjusted position in the brackets by means of set screws 15. It will thus be seen that either end of the apparatus may be raised with relation to the opposite end by adjusting the rods 12 in the brackets 13 and 14. It will, of course, be obvious that 90 if desired, the road wheels 5 may be dispensed with entirely and the wheels 10 and 11 relied upon to support the apparatus when traveling from one place to another.

The trough 8 is provided in each of its side walls with a vertical slot 16 and a horizontal slot 17 in communication with each other, and within the lower part of the trough is mounted an open-ended carrier 18, the side walls of which are preferably 100 formed partly solid and partly of interwoven wire, as shown clearly in Fig. 2. On the inner side of each of the side walls of

- the trough 8 are supported a plurality of rollers 19 for supporting the carrier 18, and which carrier is provided with a pair of trunnions which project through the slots in 5 the side walls of the trough and have secured thereto outside of said trough a pair of levers 20, each adapted to coöperate with a pulley 21 mounted on the outside of each of the side walls of the trough for swinging 10 the carrier to a vertical position in the manner hereinafter described. A vertically slidable rack bar 22 is mounted in a pair of slideways 23 at each side of the trough 8, immediately below the vertical slots 16, and 15 the upper ends of the rack bars are formed to act as bearings for the trunnions carried by the carrier 18. Mounted for rotation in the beams 6 are a pair of shafts 24, each provided at one end thereof with a sprocket 25, whereby motion is transmitted from one shaft to the other by means of a crossed chain 26 engaging said sprockets, so that, on the rotation of one of said shafts, the other will rotate in the opposite direction. 20 Each of the shafts 24 has secured thereto a pinion 27, which pinions engage the rack bars 22 at opposite sides of the trough 8. One of the shafts 24 is provided with a crank handle 28 for manually rotating the shaft. 25 The operation of the carrier will be described in connection with the operation of the entire apparatus.
- A pair of cross beams 29 are secured between the beams 6 at one end of the apparatus, and these cross beams support an engine illustrated diagrammatically at 30 for operating the apparatus. Power is transmitted from the engine by means of a pulley 31 and belt 32 to a countershaft 33, which is 30 supported in bearings secured to the upper side of the beams 6. This countershaft carries at each end thereof a pair of clutch members, which are shown herein only diagrammatically at 34 for transmitting the motion of the shaft to a flexible shaft 35 at each end of the shaft 33. At the opposite end of one of the shafts 35 is carried a rotary knife 36 mounted in a casing 37. The bearings for said knife in the casing 37 are 35 preferably ball-bearings, and the knife is adapted to be rotated from the flexible shaft when the engine is running. On the upper side of the casing 37 are mounted two pair of handles 38 for manually guiding the knife 36 in its movement. At the free end of the flexible shaft at the opposite end of the countershaft 33, is carried a similar housing 39 in which is also mounted for rotation by the flexible shaft 35 a knife 40. 40 This knife, however, is intended for operation in a vertical plane, and for that purpose a shaft 41, Fig. 3, is secured to one of the side walls of the trough 8 and extends transversely to a suitable distance from the apparatus, and the housing 39 is provided

with a journal bearing 42 that pivots around said shaft 41. The housing 39 is also provided with a handle 43 pivotally secured thereon and having at its lower end a crank 44, by means of which handle the knife may 70 be swung into and out of position for use and pressure exerted on the handle while the knife is in use for cutting off the tops of the sugar canes.

The operation of the machine is as follows: The machine is drawn by any suitable power to the side of the cane field from which the cane is to be cut, the side of the machine carrying the knife 36 being toward the cane field and as near as possible to the 75 stool of cane. The engine is started and the knife 36 thereby put in rotation. Two operators grasp the handles 38 and guide the knife so as to bring it in contact with the cane at the root thereof. The operation of 80 the engine may be stopped as soon as sufficient cane is felled to fill the trough 8. The cane which is felled will either fall over into the trough 8 or be manually placed therein, with the tops all at the same side of the 85 machine. The object of having the trough wider at the top is to insure that any canes falling toward the machine will be directed into the trough. The canes which have fallen or been placed in the trough will thus 90 be lying in the carrier 18, with their tops all at the side of the machine farthest from the knife 36. As soon as all the canes from the 95 stool have been cut and placed in the carrier, they are fastened therein by means of 100 chains or ropes, not shown. An operator then grasps the handle 28 and rotates the shafts 24, whereupon the pinions 27 engage the rack bars 22, the upper ends of which are at this time in engagement with the trunnions carried by the carrier 18, as shown in Fig. 2, whereby the ascent of the rack bars will move the carrier upward, the carrier being guided in its upward movement by the trunnions projecting through the slots 16 in 105 the sides of the trough. During the upward movement of the carrier, the levers 20 secured to the trunnions engage the pulleys 21, as shown in dotted lines in Fig. 4, the carrier being thereby gradually swung 110 on the upper end of the rack bars so that when the trunnions arrive at the top of the slots 16, the carrier will be in the vertical position shown in full lines in Fig. 4, whereby the tops of the canes will be in contact 115 with the bottom of the trough 8, in which position the weight of the canes will cause them to settle down so that the "tops" will be practically all on the same level horizontally. The chains or ropes may then be 120 tightened so as to secure them in this position. The handle 28 is then operated so as to rotate the shafts 24 in the opposite direction from that above described, whereupon the rack bars will descend and thus return 125 130

the carrier to return to its normal position as shown in Fig. 2, the operation of the handle being continued until the rack bars have entirely released the trunnion of the carrier, as shown for instance in Fig. 5, so that the carrier now rests on the rollers 19. The carrier is then pushed toward the knife 40 until the tops of the canes are at the proper point below said knife to be cut off from the cane, whereupon the engine is again set in motion, thereby rotating the knife 40 and the knife is swung by means of the handle 43 into the proper position to contact with the canes in the carrier, and by exerting pressure on the crank 44 of the handle 43 while the knife is rotating, all the tops of the canes in the carrier will be cut off. This operation is called the "topping" of the canes. After this is accomplished, two operators may take hold of the levers 20, after having swung the knife 40 on the shaft 41 out of the way, and swing the carrier on its trunnion to the position shown in dotted lines in Fig. 5, whereupon the chains or ropes may be released and the cane will fall out of the carrier ready to be taken to the grinding mill.

It will be understood, of course, that the raising of the carrier may be accomplished by transmitting power from the engine, instead of by hand as herein described, if desired, and that the motion may be transmitted from one of the shafts 24 to the other by means of gearing instead of chain and sprockets, and while I have described in detail these features and the other features of construction herein illustrated, it is to be understood that I do not thereby limit my invention to the specific structure herein illustrated, as I am aware that many mechanical changes and modifications may be made therein without departing from the spirit and scope of the invention as set forth in the claims appended hereto.

Having thus described my invention, what I claim is:

1. In a machine of the character described, the combination of a vehicle, a trough mounted on said vehicle, a horizontally disposed rotary knife at one end of said trough, a vertically disposed rotary knife at the opposite end of the trough, means carried by said vehicle for rotating said knives, a vertically movable carrier within said trough, and means for partially rotating said carrier during its vertical movement.

2. In a machine of the character described, the combination of a vehicle, a trough mounted on said vehicle, a horizontally disposed rotary knife at one end of said trough, a vertically disposed rotary knife at the opposite end of the trough, means carried by said vehicle for rotating said knives, a carrier within the trough and provided at each side thereof with a trunnion, a pair of guides

secured to each side of said trough, a vertically movable rack bar carried by said guides in position to engage each of said trunnions, and means for operating said rack bars thereby to raise said carrier.

3. In a machine of the character described, the combination of a vehicle, a trough mounted on said vehicle, a horizontally disposed rotary knife at one end of said trough, a vertically disposed rotary knife at the opposite end of the trough, means carried by said vehicle for rotating said knives, a carrier within the trough and provided at each side thereof with a trunnion, a pair of guides secured to each side of said trough, a vertically movable rack bar carried by said guides in position to engage each of said trunnions, means for operating said rack bars thereby to raise said carrier, and means for partially rotating said carrier during its upward movement.

4. In a machine of the character described, the combination of a vehicle, a trough mounted on said vehicle, a horizontally disposed rotary knife at one end of said trough, a vertically disposed rotary knife at the opposite end of the trough, means carried by said vehicle for rotating said knives, a carrier within the trough and provided at each side thereof with a trunnion, a pair of guides secured to each side of said trough, a vertically movable rack bar carried by said guides in position to engage each of said trunnions, means for operating said rack bars thereby to raise said carrier and means for partially rotating said carrier during its upward movement, said means comprising an arm secured to each of said trunnions and a trip member carried by said trough in the path of said arm.

5. In a machine of the character described, the combination of a vehicle, a trough mounted on said vehicle, means at one end of said trough for felling cane, means at the opposite end of the trough for topping the cane, means carried by the vehicle for operating said felling and topping means, and a carrier within said trough and movable vertically and transversely with respect to the trough and means for imparting movement to said carrier.

6. In a machine of the character described, the combination of a vehicle, a trough mounted on said vehicle, means at one end of said trough for felling cane, means at the opposite end of the trough for topping the cane, means carried by the vehicle for operating said felling and topping means, a carrier within said trough and movable vertically and transversely with respect to the trough, means for imparting movement to said carrier and means for partially rotating said carrier during its vertical movement.

7. In a machine of the character described,

the combination of a vehicle, a trough mounted on said vehicle, means at one end of said trough for felling cane, means at the opposite end of the trough for topping the cane, a carrier within said trough for receiving the felled cane and delivering it to the topping means, means including a

pair of slidable rack bars for moving said carrier vertically, a pair of shafts carrying pinions in engagement with said bars, and means for rotating said shafts in opposite directions.

M. WERTHEIM.
